UNITED STATES PATENT OFFICE

125,339

DESIGN FOR A COMBINED MASK AND HAIR NET

Leah G. Jaslow, New Bedford, Mass.

Application November 23, 1940, Serial No. 96,748

Term of patent 3½ years

To all whom it may concern:

Be it known that I, Leah G. Jaslow, a citizen of the United States, residing at New Bedford, in the county of Bristol and State of Massachusetts, have invented a new, original, and ornamental Design for a Combined Mask and Hair Net, of which the following is a specification, reference being had to the accompanying drawing, forming part thereof.

I claim:

The ornamental design for a combined mask and hair net, as shown.

LEAH G. JASLOW.
